UNITED STATES PATENT OFFICE.

REX G. HAMAKER, OF HOUSTON, TEXAS.

CABLE BEARING FOR WALKING BEAMS.

Application filed June 27, 1924. Serial No. 722,863.

To all whom it may concern:

Be it known that I, REX G. HAMAKER, a citizen of the United States, residing at Houston, in the county of Harris and State 5 of Texas, have invented certain new and useful Improvements in a Cable Bearing for Walking Beams, of which the following is a specification.

This invention relates to new and useful 10 improvements in a cable bearing for walking beams.

One object of the invention is to provide an attachment of the character described specially designed to be attached to the 15 walking beam, and forming a bearing in which the pump operating cable works.

The walking beam commonly used in pumping wells is pivoted on a standard and connected at one end to the power through 20 which it is reciprocated. At its other end the walking beam is connected to the polish rod of the pump by means of a rod clamp secured to the rod, and a cable which is attached to the rod, and works in a cable bearing 25 on the last named end of the walking beam. An object of this invention is to provide an improved type of bearing designed to be attached to said beam, and in which the cable may work without substantial in- 30 jury to the cable.

Another object of the invention is to provide an attachment of the character described which may be readily fitted to the walking beam without cutting or shaping 35 the end of the walking beam to receive the same.

A further feature of the invention resides in the provision of an attachment of the character described so formed that in 40 operation a direct upward pull will be exerted through the cable on the pump polish rod, so that said rod will not become bent or worn in an uneven manner, as it is operated.

A still further feature of the invention 45 resides in the provision of a cable bearing of the character described which is pivotally connected to the walking beam so that the bearing may be swung out of the way when it is desired to pull the pump rods, so 50 as not to interfere with said work, and which includes also means for holding said bearing in a fixed position, relative to the walking beam during the operation, of the pump.

With the above and other objects in view, 55 the invention has particular relation to cer-

tain novel features of construction, operation and arrangement of parts, an example of which is given in this specification and illustrated in the accompanying drawings, 60 wherein:

Figure 1 shows a fragmentary side view of a walking beam, showing the cable bearing attached thereto with the operating cable therein connected to the pump rod. 65

Figure 2 shows a fragmentary side view of the walking beam with the cable bearing attached thereto, and shown in dotted lines in operative position, and in full lines swung into position so as not to interfere 70 with the work of pulling the pump rods.

Figure 3 shows a fragmentary plan view thereof.

Figure 4 shows an end view; and,

Figure 5 shows a side elevation of a walking beam mounted on its standard. 75

Referring now more particularly to the drawings, wherein like numbers of reference designate similar parts in each of the figures, the numeral 1 designates an upright standard on which the walking beam 2 is pivoted. The numeral 3 designates the pump tubing with the usual stuffing box 4 at its upper end through which the pump polish rod 5 works in pumping a well. 80 The numeral 6 designates a polish rod clamp of conventional construction, which is clamped on the polish rod. 85

One end of the walking beam is connected to the power through which said beam is 90 oscillated. This connection has not been shown as it is in common use. Pivoted to opposit sides of the other end of the walking beam are the arcuate cable guides 7, 7. 95

These guides are fastened to the walking beam, preferably by means of a suitable bolt as 8 which passes through them and through the walking beam. However, other means of pivoting the guides to the walking beam may be employed. At their upper ends these guides are widened inwardly 100 forming lugs or seats as 9, 9, which rest against the upper side of the beam during the operation of the pump. These guides are provided with grooves as 10, 10. There

is a looped cable 11 whose ends are attached to the clamp 6 on opposite sides, the arms of the cable working in the respective grooves 10, 10, and the looped portion thereof of working in grooves as 12 formed in the lugs 9, 9, said grooves 10 and 12 forming in 105 effect a substantially U-shaped bearing in

110

which the looped cable 11 works. The cable bearings 7 are substantially arcuate as stated and form arcs of circles having their centers in the center of the pivotal mounting of the walking beam. The polish rod is thus substantially tangential to these cable bearings at all times of the operation of the walking beam, and as a consequence a direct upward pull is exerted on said rod, thus preventing the bending or uneven wearing of the same.

These guides also converge downwardly, to coincide with the downwardly converging ends of the cable 11. While the pump is being operated, it is necessary that the cable guides or bearings be held in a fixed position with reference to the walking beam, and for that purpose there is a jointed brace 13 for each guide. Each brace is formed of two sections 14 and 15, which are pivoted together at one end, and whose other ends are pivoted to the walking beam, and the respective guides 7. These sections are preferably formed of angle iron, and when in substantially aligned position they hold the guides 7 in fixed or working position, the section 14 having an extended overlapping flange 16 which engages against the corresponding flange of the section 15 so as to form a one way joint. When it is desired to disconnect the pump rod from the walking beam for the purpose of pulling said rods, the toggle joint between the sections 15 and 14 will permit the swinging of the guides 7 inwardly toward the walking beam as indicated in Figure 2, so as to be out of the way and not to interfere with the work of pulling said rod.

What I claim is:—

- 40 1. An attachment for walking beams including a pair of guides adapted to be pivotally connected to opposite sides of the beam and forming a bearing, for a flexible connecting member.
- 45 2. An attachment for walking beams including a cable bearing adapted to be pivotally connected to said beam, and means for preventing the movement of said bearing relative to said beam.
- 50 3. An attachment for walking beams including a pair of guides pivotally connected to opposite sides of the beam and forming a cable bearing, and means connected to the beam and to the respective guides, and adapted to hold the guides in fixed relation to said beam.
- 55 4. An attachment for a walking beam formed with a transverse cable bearing, and depending guides spaced apart, and pivotally connected to the beam and forming cable bearings.
- 60 5. An attachment for a walking beam formed with a transverse cable bearing, and depending guides spaced apart, and adapted to be pivotally connected to the beam and

forming cable bearings, and means adapted to hold said guides in fixed position relative to the beam.

6. An attachment for a walking beam including a cable bearing adapted to be swung from said beam, and a jointed brace member adapted to be connected to said beam and to said bearing.

7. An attachment for a walking beam including a pair of cable guides adapted to be swung from said beam and spaced apart, and a brace for each guide adapted to be connected to the beam and to the corresponding guide.

8. An attachment for a walking beam including a pair of cable guides adapted to be pivoted to said beam and spaced apart, a jointed brace for each guide, said braces being adapted to be connected to the beam and to the respective guides.

9. In a well pumping apparatus a walking beam having arcuate side guides, one on each side, said guides forming bearings for a connecting member, a brace connected to the walking beam and to each guide and normally holding said guides in working relation with the beam, said braces being releasable to permit the guides to swing into inactive position.

10. In a pumping apparatus, a support, a walking beam having a pivot bearing on said support, and having arcuate side guides forming bearings, said guides forming arcs of circles which are concentric with the pivot bearing, braces connected to the respective guides and to the walking beam and normally holding said guides in working relation with said beam, said braces being releasable to permit the guides to swing inwardly toward the support into inactive position.

11. In combination a pivotally mounted walking beam, a pump rod, means connecting said pump rod to said beam, guiding means on opposite sides of said beam adapted to maintain said connecting means in vertical alignment with respect to the pump rod during the operation of the rod, braces normally maintaining said guiding means in fixed working position relative to the beam, said braces being releasable to permit said guiding means to swing into inactive position.

12. An attachment for a pivotally mounted walking beam, including a bearing for a flexible connecting member, said bearing having an extended lower end capable of movement, in substantially a vertical plane, relative to the walking beam, means for fixing said lower end against such movement, said means being releasable to permit such movement.

13. An attachment for walking beams including a pair of bearings adapted to have a swinging movement with relation to the

beam, and to be arranged, one on each side of the beam, means provided to connect said bearing to said beam to prevent such relative swinging movement, said means being 5 releasable to permit such movement.

14. An attachment for walking beams including a guide adapted to be pivotally connected to the side of said beam and to depend therefrom, said guide forming a bearing 10 for a flexible connecting member.

15. An attachment for a walking beam, said beam being adapted to be mounted on a pivot bearing, said attachment including an 15 arcuate guide which forms an arc of the circle concentric with said pivot bearing, said guide being pivotally connected to said beam and depending therefrom and forming a bearing for a flexible connecting member.

20 16. An attachment for a walking beam in-

cluding a bearing for a flexible connecting member, said bearing being adapted to be supported by said beam, depending guides adapted to be associated with the beam, one on each side thereof, said guides forming 25 bearings for said connecting member, and means adapted to connect the guides with the beam, said connecting means being formed to normally hold the guides in fixed relation to the beam and also to permit the 30 movement of said guides relative to the beam.

In testimony whereof I have signed my name to this specification in the presence of two subscribing witnesses.

REX G. HAMAKER.
